UNITED STATES PATENT OFFICE

2,514,659

PUNCH PRESS

Eugene F. McClung, Los Angeles, Calif.

Application April 19, 1946, Serial No. 663,334

5 Claims. (Cl. 164—89)

1

My invention relates to a punch press and more particularly to a machine for punching and cutting segments or links. The present machine is an improvement upon that shown in my Patent No. 2,144,684, issued January 24, 1939.

An object of the present invention is to provide means in the work material itself for centering the material for cutting.

Another object is to provide means whereby twice as many segments or links can be cut from the same length of material.

Still another object is to provide means for cutting from the work material fillers or washers to be used in mats made from the segments or links, without sacrificing any of the material that might otherwise be used for the segments or links.

My invention also has for its objects to provide such means that are positive in operation, convenient in use, easily installed in a working position and easily disconnected therewith, economical of manufacture, relatively simple, and of general superiority and serviceability.

The invention also comprises novel details of construction and novel combinations and arrangements of parts, which will more fully appear in the course of the following description. However, the drawings merely show and the description merely describes one embodiment of the present invention, which is given by way of illustration or example only.

In the drawings, like reference characters designate similar parts in the several views.

Fig. 1 is a broken, vertical sectional view of parts of a punch press embodying my present invention.

Figs. 2 to 6 are sections taken on the lines 2—2, 3—3, 4—4, 5—5 and 6—6, respectively, of Fig. 1.

Fig. 7 is a bottom plan view of the cutting die and associated parts.

Fig. 8 is a plan view of work material, illustrating how it is punched and cut.

Reference is made to my co-pending application, Serial No. 663,335, filed contemporaneously herewith, but now abandoned, for subject matter shown and described but not claimed herein.

Referring more in detail to the drawings, Fig. 1 is a fragmentary view of a punch press. Remaining parts are illustrated in Fig. 1 of my said patent. However, Fig. 1 is believed sufficient for anyone skilled in the art to understand the construction and operation of my present improvements.

The reciprocating ram of the punch press is suggested at 10. A block 12 is mounted on the ram 10 for reciprocation therewith. A front clamping plate 13 is clamped to the block 12 by bolt and nut means 14 and 15. Customary, complementary, V-shaped (in plan) recesses 16 and 17 in the plate 13 and block 12 receive pin means

2

18 on a top plate 19 of the cutting device. The top plate 19 has an underneath, longitudinal groove 20. A flat spring 21 is arranged in the groove 20 for a purpose hereinafter more fully described.

A body 22 of the cutter carries on the underside thereof four smaller cutters 23 to 26 placed two-by-two, as best shown in Fig. 7. Centrally of the four smaller cutters is a larger cutter 27. Guides 28 to 35 have rounded noses 36 for centering work material 49 between same. The guides are arranged in two parallel rows of 28 to 31 on one side, and 32 to 35 along the other side, as shown in Fig. 7.

Between the guides 30 and 31 on one side and guides 34 and 35 on the other side is arranged a T-shaped cutter comprising blades 38, 39 and 40. The blade 38 is the top of the T, while the aligned blades 39 and 40 constitute the tail of the T. Adjacent ends of the blades 39 and 40 are embedded in a central guide 41. The guide 41 has a round nose 42 for engaging the relatively large opening 43 cut by the cutter 27, to center the segment or link for the cutting step. The blades 38 to 40 are mounted in a base 44 that is bolted on the underside of the body 22, as suggested at 45.

A stripper plate 46 is arranged on a bed member 47 that has a longitudinal slot 48 therealong for feeding the work material 49 into the machine. A relatively soft metal plate 50 is laid along the floor of the slot 48 in the portion thereof opposite the cutters. The bed 47 rests on a base 51 that in turn is supported by a frame member 52 of the machine.

Punches 53 reciprocate in aligned openings 56 and 57 in the base 51 and the bed 47. A punch 54 reciprocates in aligned openings 58 and 59 in the base 51 and bed 47, while punches 55 reciprocate in aligned openings 60 and 61 in the base 51 and bed 47. The punches 53 are arranged, when reciprocated, to punch plugs 62 out of the upper ends of the hollow cutters 23 and 26, as shown in Fig. 2. The punch 54 is arranged, when reciprocated, to punch plugs 63 out of the upper end of the hollow center cutter 27, as shown in Fig. 4. The flat spring 21 is inclined to tip the top plug 53 rearwardly, so that there can be no jamming of the plugs 63 in the groove 20. The punches 55 likewise push the plugs out of the cutters 23 and 24 and into the groove 20.

It will be noted that the groove 20 is inclined downwardly so that the plugs pushed from the cutters will roll or settle downward and fall rearwardly from the groove 20 by reason of the reciprocation of the body 22 and top plate 19. Suitable separating means for the different sizes of the plugs may be employed, if desired. The plugs 60 63 are preferably used as spacers and the like in

formats made from the finished product of my present machine.

Reciprocating means for the punches 53, 54 and 55 comprises a plate 66 upon which the said punches are fixedly mounted. The plate 66 is in turn mounted upon a movable frame 67 that is arranged to be reciprocated on frame means 68 by a cam 69 on a shaft 70 that is driven by suitable means and timed to punch the plugs from the cutters and from the material after each punching operation. A coil spring 71 is hooked to a bracket 72 under the frame member 52 and to a lug 73 on the movable frame 67, to raise the movable frame 67 and thereby the punches 53 to 55, when permitted by the cam 69. The enlargement of the cam 69 causes the retractive movement of the movable frame and punches. A slot 74 permits longitudinal movement of the frame 67 relative to the shaft 70.

A mutilated, toothed feeding wheel 75 is rotated counterclockwise, as indicated by the arrow A, by means of the shaft 76 which is driven by the common power source (not shown) for the machine.

In the operation of the machine, the work material 49 is manually fed under the wheel 75, the toothed portion of which advances the material between the guides 28, 29, 32 and 33 to a position under the cutters 23 to 27. The feeding wheel 75 having reached approximately the position shown in Fig. 1, further advance of the work material is temporarily halted while the cutters descend and cut the four smaller holes 77 to 80 and the larger opening 43 in the material. After the cutters have been withdrawn, the intermittent feed is again resumed by the wheel 75, until the punched part of the work material is below the blades 38 to 40. Descent of the guide 41 into the opening 43 slightly ahead of the blades, as suggested in Fig. 6, centers the material so that the cross blade 38 severs the links or segments 81 and 82 from the main body of the work material 49 along the correct line 83. At the same time the blades 39 and 40 cut the links or segments 81 and 82 apart along the line 84, forming two links side-by-side. The links 81 and 82 are caught as they fall from the rear end of the groove 48. They are then ready to be assembled in a mat.

The stripping plate 46 permits the cutters to be withdrawn from the material while holding the material down.

While I have illustrated and described what I now regard as the preferred embodiment of my invention, the construction is, of course, subject to modifications without departing from the spirit and scope of my invention. I, therefore, do not wish to restrict myself to the particular form of construction illustrated and described, but desire to avail myself of all modifications that may fall within the scope of the appended claims.

Having thus described my invention, what I claim and desire to secure by Letters Patent is:

1. In a punch press, a reciprocating ram, mechanism to feed work material, hollow punch means on the ram arranged to punch a hole in the work material, rod means disposed to push plugs of the material longitudinally out of the punch means, and spring means arranged to yieldingly push the plugs laterally of said longitudinal direction for discharging same.

2. In a punch press, a reciprocating ram, mechanism to feed work material, hollow punch means on the ram arranged to punch a hole in the work material, rod means disposed to push plugs of the material longitudinally out of the punch means, spring means arranged to yieldingly push the plugs laterally of said longitudinal direction for discharging same, cutting means disposed to cut the material in a succeeding step in the operation, and centering means arranged to engage the hole in the work material punched in the punching step, to center the material for cutting same.

3. In a punch press, a reciprocating ram, mechanism to feed work material, guide means on the ram arranged to reciprocate therewith to position the work material, punch means on the ram disposed to punch a hole in work material so positioned, cutting means mounted on the ram to cut the material when the mechanism advances the work material beyond the punching area, and centering means arranged to engage the hole in the work material punched in the punching step, to center the material for cutting same.

4. In a punch press, a reciprocating ram, mechanism to feed work material, tapering guide means on the ram arranged to reciprocate therewith to position the work material, punch means on the ram disposed to punch a hole in work material so positioned, cutting means mounted on the ram to cut the material when the mechanism advances the work material beyond the punching area, and centering means arranged to engage the hole in the work material punched in the punching step, to center the material for cutting same.

5. In a punch press, a reciprocating ram, mechanism to feed work material, hollow punch means on the ram arranged to punch a hole in the work material, stripper means for preventing the material from following retracting movements of the punch means, rod means disposed to push plugs of the material from the punch means, cutting means mounted on the ram and disposed opposite a succeeding stop of the work material to sever portions from the strip material and to cut the portions into segments having complementary parts of the hole, and means to severally discharge from the press the plugs and the said segments.

EUGENE F. MCCLUNG.
